UNITED STATES PATENT OFFICE.

IWANE KOUTKINE, OF ST. PETERSBURG, RUSSIA.

SPARKING PLUG.

1,070,266.

Specification of Letters Patent.

Patented Aug. 12, 1913.

Application filed May 8, 1912. Serial No. 695,988.

To all whom it may concern:

Be it known that I, IWANE KOUTKINE, student, a subject of the Czar of Russia, residing at 34 Foutanka, St. Petersburg, Russia, have invented certain new and useful Improvements in Sparking Plugs, of which the following is a specification.

The present invention relates to a sparking plug for internal combustion engines, and has for its object to provide a plug in which those portions most liable to wear and to clogging by impurities can be easily and quickly removed and replaced, repaired or cleaned.

Another object of the present invention is to improve its construction so as to insure the reliability of its operation.

The invention is illustrated by way of example, in the accompanying drawings in which—

Figure 1 is an elevation of the improved sparking plug, Fig. 2 is a plan thereof and Fig. 3 a section on the line A—B of Fig. 2 while Fig. 4 is a section on the line C—D of Fig. 3. Fig. 5 is an elevation showing the improved arrangement of sparking-points, while Fig. 6 and Fig. 7 are sections respectively on the lines AB and CD of Fig. 5.

In accordance with the present invention the sparkling plug consists of a casing 1 adapted to be screwed into the cylinder wall and which is provided with a conical passage 2. In this passage is arranged an insulating body 3 also of conical form, and which is spaced from the casing by a packing 4.

The body 3 has an extension 5 on which rests a bayonet ring 6. This ring is provided with two or more screw-threaded pins 8 horizontally arranged as shown in Fig. 3. On these pins are provided wing nuts 9 and collars 11 of suitable form. The pins 8 are arranged in spiral slots 12 in the casing 1 which slots are connected with the vertical slots 13. The pins 8 are introduced by way of the latter are fed forward by rotation of the bayonet ring and are secured by means of the nuts 9. By rotation of the bayonet ring 6 the member 3 is forced tightly into the opening 2. A conductor 14 passes through the body 3 and terminates in the sparking points 15. To the upper end 16 is secured the plug for connecting the spark-

ing plug with the source of current. If the 55 sparking points 15 are to be renewed or cleaned and for this purpose the body 3 is to be removed from the casing 1 it is merely necessary to unscrew the nuts 9 and to turn the bayonet ring 6 until the pins 8 come 60 against the slots 13. The ring 6 can then be removed and thereupon the body 3 can also be removed.

In order to improve the construction described above as to the reliability of its operation the sparking-plug can be provided with the improved arrangement of sparking points, substantially as described below and illustrated on Fig. 5, 6, 7 in the accompanying drawings.

Sparkling plugs provided with more than one sparking point or, as it is often the case in many constructions, provided with the starlike arrangement of sparking-gaps ordinarily become clogged by impurities after 75 some time, so that no sparks can be produced.

The present invention has for its object to obviate this inconvenience. For that purpose the conductor *a* (Fig. 5) terminates in 80 the four cornered or polyhedral pin *b* provided with sharp edges passing through the corresponding circular opening *c* in the bottom *d* of the casing *f*. In this manner 85 sparkling-gaps are formed between the edges of the conductor *a* and the circumference of the opening *c*. Beside these sparkling-gaps another set of such sparkling-gaps is formed in accordance with the present invention between the edges of the four cornered or polyhedral collar *g* and the internal surface of the casing *f*. These latter sparkling gaps are arranged inside the said casing *f*, so that they can by no way become dirty. The spark therefore must be in any case produced 95 at *g*, even if the external set of sparkling-gaps is becoming dirty and out of operation. The gas inside the plug being inflamed, it comes to movement with great velocity so that the sparkling gaps at *b* are blown 100 through with force sufficient to make them clean from dirt. The sparkling-gaps at *g* act therefore in a certain manner as emergency gaps. They must be for some extent greater than the sparkling gaps at *b*, but in 105 any case must correspond to the given electrical tension.

Having now particularly described and

ascertained the nature of my said invention and in what manner the same is to be performed I declare that what I claim is:

5 In a spark plug, a casing having bayonet slots therein; a shouldered body carrying a conductor removably fitted in said casing; a ring revolvably encircling said body and adapted to rest upon the shoulder; threaded pins projecting from said ring adapted to

engage the bayonet slots to bind said body 10 within said casing; and nuts run upon said pins for locking the same in the slots.

In testimony whereof I affix my signature in presence of two witnesses.

IWANE KOUTKINE.
